(Cl. D9—2)

To all whom it may concern:

Be it known, that we, Lars Johan Faith-Ell and Ture Emanuel Lindahl, subjects of the King of Sweden, residing at Stockholm, Sweden, and Hagersten, Sweden, respectively, have invented a new, original, and ornamental Design for a Suction Cleaner Nozzle, of which the following is a specification, reference being had to the accompanying drawing, forming a part thereof.

In the drawing,

Fig. 1 is a front perspective view of a suction cleaner nozzle showing our design;

Fig. 2 is a front perspective view with the nozzle inverted from the position shown in Fig. 1; and

Fig. 3 is a rear perspective view with the nozzle in the position shown in Fig. 1.

What we claim is:

The ornamental design for a suction cleaner nozzle, as shown and described.

LARS JOHAN FAITH-ELL.
TURE EMANUEL LINDAHL.
